UNITED STATES PATENT OFFICE.

JOHN L. CREVELING, OF NEW YORK, N. Y., ASSIGNOR TO SAFETY CAR HEATING & LIGHTING COMPANY, A CORPORATION OF NEW JERSEY.

ELECTRIC-LIGHTING SYSTEM FOR CARS.

1,145,468.

Specification of Letters Patent.

Patented July 6, 1915.

Application filed May 28, 1908. Serial No. 435,377.

To all whom it may concern:

Be it known that I, JOHN L. CREVELING, of New York, in the county of New York and State of New York, have invented a 5 certain new and useful Improvement in Electric-Lighting Systems for Cars, as set forth in the annexed specification and drawing, forming a part thereof.

My invention pertains to that class of 10 electric lighting systems for cars or other moving vehicles in which current is produced by a generator carried by the car and driven by motion derived by the motion of said car, and a storage battery is used to 15 furnish current when the car is running at a low speed or standing.

The principal object of my invention is to 20 provide a system having means whereby the generator may be so driven by the motion of the car that when it shall be delivering a pre-determined output further increase in the speed of the car will not cause a corresponding increase in the output delivered by the generator, but the energy so delivered will 25 remain practically constant within reasonable limits of speed. I also provide means whereby when the batteries shall have become sufficiently charged that their voltage shall have increased beyond certain limits 30 resistance will be automatically inserted in the lamp or translating circuit to compensate for such rise in voltage of the batteries.

In the drawing Figure I shows a general 35 view of the generator and driving mechanism and a diagrammatic view of the remainder of my improved lighting system. Fig. II shows a section of one form of driving pulley mechanism comprehending means whereby the generator output is held constant within certain limits. Fig. III shows a section of another form of such driving mechanism.

Like numbers in the several figures are used to indicate like parts.

45 In Fig. I (1) represents an ordinary car wheel and (2) the ordinary axle thereof, upon which is mounted the driving pulley (3) by the side of which are placed the idlers (4) in a manner as shown and described in a patent to me #691359 of January 21st, 1902.

(5) represents a generator suspended from the lower side of the car floor directly over the axle (2). This generator is pro-

vided with driving pulleys (6) carried by 55 the rods (7) and arranged in such manner that when they are driven in opposite directions one of the pulleys (6) engages the armature shaft and the other pulley (6) runs idle and if their directions be reversed the 60 other one will engage the shaft and its opposite will run idle, then if properly connected to the axle the armature may be driven in a constant direction regardless of the direction of the motion of the car. The 65 construction of this type of generator is clearly set forth in Patents #709,848 granted to me Sept. 28, 1902, and #721,025 granted to me Feb. 17, 1903.

An endless belt (8) is looped over one of 70 the pulleys (6) and passed around the driving pulley (3) and idlers (4) and then looped over the other pulley (6) so as to operatively connect the generator with the 75 axle.

In my prior patents above referred to the 75 generator produces a reversible, intermittent, and variable current, by reason of the fact that the pulleys 6 are so connected with the axis of the armature that the direction 80 of motion of the car connects the proper clutch *g*, *h*, and that clutch, together with the action of its spring *o* upon the parts *p* and *m*, always impart to the armature motion in the same direction, the pulley at the 85 other end of the armature running idle, as fully disclosed in said patents.

The lead (9) is brought from one terminal of the generator to one side of the storage battery (10) and thence to one terminal 90 of the lamp switch indicated at (11) from the other terminal of which leads the wire (12) to the lamps or other translating devices indicated at (13). The other generator lead is brought to one terminal of an 95 automatic switch diagrammatically indicated and this switch 15 is controlled automatically by an electromagnet connected to the circuit of the generator in a manner well understood by those versed in the use 100 of automatic switches of this kind. The function of the switch is to close the circuit when the voltage of the generator rises to the voltage of the battery and to open the circuit when its voltage falls a little below 105 that of the battery.

A switch well adapted to be used in this system is shown and described in Patent

#707763 granted to me on August 26, 1902. From the other side of this switch is led the wire (16) to one terminal (17) of the resistance device (18) from the other terminal (19) of which the wire (20) leads to one terminal of the resistance device (21) from the other terminal of which the wire (22) leads to the remaining terminals of the lamps or other translating devices, (13).
 10 The resistance device or regulator (18) comprehends the contact member (23) the position of which determines the amount of resistance (24) that shall be inserted between terminals (17) and (19) in series with
 15 the lamp circuit. This movable contact is attached to the core (53) of the solenoid (54) which is in shunt across the battery as by wires (55) and (56) and current in the said solenoid tends to raise the core (53)
 20 against the tension of the spring (57) which is adjustable by the means of screw (58).

The resistance device (21) is an ordinary manually operated device which may be used to insert more or less resistance (25) in series with the lamps as may be desired.
 25

In Fig. II (2) represents the car axle, (3) the driving pulley (4) one of the idlers and (8) the driving belt as shown in Fig. I. The pulley (3) is provided with a hub (26) revolvably mounted upon the sleeve (27) fixed upon the axle. The web (28) of the pulley (3) is provided with perforations which engage the webs (29) of the annular shoes (30) which face the annular shoes (31) provided with the webs (32) which engage perforations in flange (33) carried by the hub (34) which is keyed as by the key (35) upon the sleeve (27) in such manner that it revolves with the said sleeve, and
 30 is free to move laterally upon the same. The compression spring (36) adjustable as by the nut (37) engaging the screw portion (38) of the sleeve (27) serves to hold the faces of the annular shoes (30) and (31) in
 35 close adjustable contact and to force the hub (26) against the ball bearing as indicated at (39).

In Fig. III (2) represents the car axle, (3) the pulley as shown in Figs. I and II. The sleeve (27) in this instance is provided with flange (40) the perforations of which receive the webs (41) attached to the annular shoe (42) against which is pressed the shoe (59) provided with webs (43) engaging
 40 the web portion (45) of the pulley (3) having a hub portion (44). The webs (46) engage the openings in the web (45) and carry the annular shoe (47) against which presses the annular shoe (48) provided with webs (49) engaging openings in the flange (50) which by means of spokes (51) is connected to hub (52) which hub (52) is keyed upon the sleeve (27) in such manner that it revolves therewith and that it may slide laterally thereon. The spring (36) adjustable

as by the nut (37) upon the thread (38) presses the shoe (48) against the shoe (47) and in this way moves the entire pulley in such manner that the shoe (59) is pressed against shoe (42) which is held from movement by the web (40).
 70

In Figs. II and III sleeves (27) are fixed rigidly upon the axles (2) and it is obvious that the pulley (3) in Fig. II may be revolved without moving axle (2) provided sufficient torque be applied to overcome the friction between the shoes (30) and (31) caused by the pressure exerted through the influence of spring (36), neglecting bearing friction, etc. Also pulley (3) in Fig. III
 75 can be revolved without revolving the axle if sufficient torque be exerted to overcome the friction between shoes (42) and (59) and between shoes (47) and (48) if bearing friction be neglected.
 80

To facilitate application upon the car axle the sleeve (27) may be split as also the pulley (3) and all the other annular parts designed to encircle the axle. With such arrangement it is obviously a very simple matter to separate the members carrying the friction shoes and move the shoes sufficiently that their radiating webs or projections disengage their supporting member so that they may be readily removed and replaced
 90 by new friction members or shoes which in fact are the wearing portions of the driving gear.
 95

The operation of my improved system of electric lighting is substantially as follows: Starting with the generator at rest and the various devices in the positions indicated in the drawing, if the car be started the wheel (1) will revolve as will the axle (2) and pulley (3), and by means of belt (8) transmit motion to the armature of the generator through the instrumentality of the pulleys (6) which as before described are so arranged that the motion of the armature will be in uniform direction regardless of the direction of the rotation of the pulley (3).
 100

When the generator shall have reached such a speed that its voltage shall be equal to that of the battery (10) the switch (15) will close and as soon as the generator voltage is in excess of that of the battery a current will flow through the lead (9) battery (10) switch (15) and lead (14) back to the generator. A small current also flows through the fine winding of the solenoid (54) which is connected across the battery mains by wires (55) and (56), and the current tends to cause the solenoids (54) to raise its core (53) and insert resistance (24) into the lamp circuit, between terminals (17) and (19). If this resistance device or regulator (18) be properly designed and proportioned it may be made to remain in the position indicated in the Fig. I through
 110

out the changes in the output of the generator from zero to its maximum load provided the voltage across the battery (10) shall not exceed a certain predetermined voltage which may be necessary to cause it to take its normal charging current under normal conditions. If under these conditions the lamp switch (11) be closed current will flow through the lamps or translating devices in a well known manner, and a fixed resistance may be inserted in the translating circuit to cut down the current flowing therein, if desired, as by manipulation of the resistance device (21). Now if the speed of the generator increases, the generator current will tend to increase and the torque upon pulley (3) will increase therewith. By proper adjustment of the spring (36) (see Fig. II) when this maximum desired output is reached the shoe (30) will slip upon the shoe (31) so that further increase in the speed of the axle (2) will cause no further increase in the speed of the generator. Further, the generator output will remain practically constant throughout further increase in the speed of the car, and heat generated by the friction of the shoes or friction members (30) and (31) will be rapidly dissipated by the rotating webs (29) and (32). This is also true of the other form of the driving gear, shown in Fig. III, except that the frictional driving contact takes place between shoes (42) and (59) and shoes (47) and (48) and the heat generated by the friction of such contact is dissipated by means of webs (41) and (43) and (46) and (49). While running in this manner if the regulator (18) be designed as above mentioned the said regulator will remain practically inert, that is, will not respond to the small changes in voltage necessary to raise the generator output to its maximum. If, however, the generator shall have so charged the batteries that their voltage shall begin to rise appreciably (in some instances this rise will go as high as 25%) then solenoid (54) will raise its core against the action of the spring (57) and insert the resistance (24) into the lamp or translation circuit in such manner that the high voltage across the battery terminals will not be impressed upon the translating devices which will receive approximately their normal voltage throughout quite wide changes in the voltage delivered by the generator. Now if the speed of the car and consequently the generator decrease until its voltage be a little below that of the battery (10) the switch (15) will open and cut the generator out of the circuit and thus prevent back discharge of the battery therethrough and if the lamps or translating devices still remain in circuit the voltage will gradually come down to the normal, and as the voltage lowers to the normal the regu-

lator (18) will cut out the resistance in the translating circuit, gradually as the drop takes place. If the generator be started up again the above outlined action will be repeated, etc.

I do not wish in any way to limit myself to the exact design or construction of any of the devices disclosed herein since they are merely chosen to show a system embodying my invention, and it is obvious that wide departure may be made in details without departing from the spirit of my invention.

Having thus described my invention what I consider novel and desire to protect by Letters Patent is as set forth in the following claims.

1. The herein described lighting system comprising a driving device, a driving member thereon, a generator, means for connecting the driving member to the generator, and means for connecting the driving member to the driving device for controlling the speed of said member with reference to the speed of said device.

2. The herein described lighting system comprising a driving device, a driving member thereon, a generator, means for connecting the driving device to the generator including mechanism for insuring unidirectional drive of the generator regardless of the direction of movement of said member, and means for connecting the driving member to said device to control the speed of said member with reference to the speed of said device.

3. The herein described lighting system comprising a driving device, a driving member thereon, a generator, means for connecting the driving member to the generator to operate the same, a translation circuit supplied by said generator and including a battery, means in said circuit dependent upon the battery for controlling the circuit, and means for connecting the driving member and the driving device for controlling the speed of said member with respect to said device.

4. The herein described lighting system comprising a driving device, a driving member thereon, means for connecting said device and said member for controlling the speed of said member with reference to the speed of said device, means for connecting said member to the generator including mechanism for insuring unidirectional drive of the generator, a translation circuit supplied by the generator including a battery, and means dependent upon the battery for controlling said circuit.

5. The herein described lighting system comprising a generator, a drive shaft, a pulley loosely mounted upon said shaft, annular friction plates carried by the pulley, a hub mounted upon the shaft to rotate therewith, a friction plate carried by the hub

to engage the first named friction plate, and resilient means for operating said friction plates in engagement with each other.

6. The herein described lighting system comprising a shaft, a pulley loosely mounted thereon, a friction plate carried by the pulley, friction plates mounted to rotate with the shaft, resilient means for holding said friction plates in contact with each other, a 10 dynamo having an operating shaft, a pair of pulleys on said shaft, a belt engaging all of said pulleys, and mechanism including reversely arranged clutches between the generator pulleys and the operating shaft therefor to insure unidirectional drive for the generator.

7. The herein described lighting system comprising a shaft, a loosely mounted pulley thereon, a friction plate carried by the 20 pulley, a friction plate mounted to rotate with the shaft, resilient means for forcing said friction plates into engagement, the generator having an operating shaft, means for connecting the pulley to said operating 25 shaft, a translation circuit supplied by the

generator and including a battery, and means in said circuit dependent upon the battery for controlling said circuit.

8. The herein described lighting system comprising a drive shaft, a pulley loosely 30 mounted thereon, a friction plate carried by the pulley, a friction plate mounted to rotate with the shaft, resilient means for maintaining said friction plates in engagement, the generator having an operating shaft, a 35 pair of pulleys mounted on said operating shaft, a belt passing over all of said pulleys, mechanism including reversely arranged clutches connecting the generator pulleys with the operating shaft for insuring unidirectional drive of the generator, a translation circuit connected to the generator and including a battery, and means in said circuit dependent upon said battery for controlling the circuit.
